Primary Examiner — Susan Moon Lee(74) *Attorney, Agent, or Firm* — Dennis L. Thomte; Thomte Patent Law Office LLC**(57) CLAIM**

The ornamental design for a bird feeder, as shown and described.

DESCRIPTION

FIG. 1 is a front perspective view of the bird feeder of this invention;

FIG. 2 is a top view of the bird feeder of FIG. 1;

FIG. 3 is a front view of the bird feeder of FIG. 1;

FIG. 4 is a side view of the bird feeder of FIG. 1;

FIG. 5 is a back view of the bird feeder of FIG. 1; and,

FIG. 6 is a bottom view of the bird feeder of FIG. 1.
